HAIR WAVER

Julia A. Cogswell, Jackson, Mich.

Application April 22, 1936, Serial No. 75,831

1 Claim. (Cl. 132—33)

This invention appertains to new and useful improvements in hair waving devices and more particularly to what is generally known as a hair waving rod.

5 The principal object of the present invention is to provide a hair waving rod wherein opposite ends are constructed in different sizes to permit either end to be used.

Another important object of the invention is 10 to provide a hair waving rod formed with ribs in such a manner as to cause spacing of the hair as it is wrapped on the rod to the end that waves of a more even formation can be created.

Other important objects and advantages of 15 the invention will become apparent to the reader of the following specification.

In the drawing:—

Figure 1 represents a side elevational view of the rod.

20 Figure 2 represents a top plan view of the rod. Figure 3 is a transverse sectional view through the rod.

Referring to the drawing wherein like numerals 25 designate like parts, it can be seen that the rod 5 is of elongated extent provided with reduced areas 6—7 adjacent the end A. These reduced

portions 6—7 are provided with circumferentially extending ribs 8 which extend approximately one-half the distance around the rod. The end portion B of the rod increases in diameter to the point 9 and then gradually reduces the diameter to the reduced point 10 from where it starts to increase in diameter again to the thick point 11.

Each end of the rod is provided with a short slit 12 to accommodate a spring whereby the ends 10 of the hair can be secured in place.

Obviously either end of the rod can be used to form waves depending upon the type and size desired.

While the foregoing specification sets forth the invention in specific terms, it is to be understood that numerous changes in the shape, size, and materials may be resorted to without departing from the spirit and scope of the invention as claimed hereinafter.

What is claimed is:—

A hair waving rod consisting of an elongated member provided with a pair of reduced areas adjacent one end thereof, and a rib member circumferentially disposed in each of the said reduced areas.

JULIA A. COGSWELL.
